V. WEINBERGER ET AL

MECHANISM FOR WHEELING CRIBS

Filed July 26, 1926

Patented Jan. 17, 1928.

1,656,655

UNITED STATES PATENT OFFICE.

VIKTOR WEINBERGER AND MARTIN JAKOBOWITS, OF BRONX, NEW YORK.

MECHANISM FOR WHEELING CRIBS.

Application filed July 26, 1926. Serial No. 124,891.

This invention relates generally to cribs used for babies and children, the invention having more particular reference to a novel type of mechanically and electrically driven cribs.

The invention has for an object the provision of an improved crib of the class described embodying certain novel features.

For further comprehension of the invention, and of the objects and advantages thereof, reference will be had to the following description and accompanying drawings, and to the appended claims in which the various novel features of the invention are more particularly set forth.

Fig. 1 of the drawings, is a side elevational view of a mechanically driven crib.

Fig. 2 is a similar view of an electrically driven crib.

Fig. 3 is a bottom plan view of the mechanically driven crib as illustrated in Fig. 1.

Fig. 4 is a similar view of the electrically driven crib as illustrated in Fig. 2.

Fig. 5 is a side elevational view of the driving mechanism as illustrated in Fig. 3.

Fig. 6 is a bottom plan view of the mechanism embodied in a combination mechanically and electrically driven crib.

Fig. 7 is a similar fragmentary view showing the circuit breaker.

Referring in particular to Figs. 1 and 3 of the accompanying drawings, it will be seen that we have illustrated a mechanically driven crib, which comprises a crib proper, consisting of upright supports 10, adapted to support side rails 11, a base member 12, and intermediate bars 13. The wheels 14 are rotatively attached to the lower extremities of the upright supports 10. The above described construction is such as is generally used in cribs, which are provided with suitable crib springs and a mattress, not shown in the accompanying drawings, and which are supported by the base member 12.

The coil spring 15 is positioned in the case 16, rotatively mounted in bearings 17, attached to the base member 12, and has attached thereto, and extending therefrom a crank 18 having a handle 19, as a means of winding the coil spring 15, which is held in a wound position by a ratchet 20, adapted to engage in a ratchet wheel 21. The gear 22 is attached to the case 16, and meshes with a gear 23 attached to the shaft 24, rotatively mounted in suitable bearings 25, attached to the base member 12, and has attached thereto

a disk 26, which has pivotally attached thereto, at or near its periphery, an arm 27, pivotally attached to a lever 28, which is attached to the shaft 29, rotatively mounted in suitable bearings 30, attached to the base member 12. The gear 31 is attached to the shaft 29, and meshes with a pinion 32, attached to the shaft 33, rotatively mounted in the above mentioned upright supports 10, to which are attached the wheels 14. The above described construction being such as will permit the coil spring 15 when wound, and released by the disengagement of the ratchet 20, to drive the crib forward along the floor. It will be understood that the above described mechanism may be mounted integral, that is, that the bearings above mentioned may be mounted in an integral frame member.

The worm gear 34, meshes with the worm wheel 22, and is rotatively mounted in suitable bearings 35 attached to the base member 12, and engages with a worm wheel 36, to which is operatively attached a ball governor 37, adapted to regulate the maximum speed of the unwinding of the coil spring 15, so as to limit the speed of the said crib. The said ball governor is of ordinary construction, such as is generally used, and may be set to function at various speeds by means of the lever 38, which is commonly used in connection with ball governors.

Referring in particular to Figs. 2 and 4 of the accompanying drawings, in which we have illustrated an electrically driven crib, which comprises an electric motor 39, connected by the wires 40, to a switch 41, attached to the upright support 10, and which is connected to any suitable source of electric current, not shown in the accompanying drawings, by wires of sufficient length to permit our improved crib to be driven forward and backward, the worm gear 42 is attached to the armature shaft 43 of the electric motor 39, the armature shaft 43 being further supported by a bearing 44, attached to the base member 12. The worm wheel 45, meshes with the worm gear 42, and is attached to the shaft 46, rotatively mounted in suitable bearings 47, attached to the base member 12, and the worm wheel 45 meshes with the above mentioned worm wheel 23. The above described construction being such as will permit the electric motor 39 to drive the crib forward and backward along the floor.

Refer in particular to Fig. 6 of the

accompanying drawings, in which we have illustrated a combination mechanically and electrically driven crib.

The above-mentioned worm wheel 45 meshes with the worm wheel 50, attached to the shaft 51. The worm wheel 50 has attached thereto a clutch member 52, adapted to be engaged by the clutch member 53, attached to the tubular member 57, slidably mounted on the shaft 50. The worm gear 58 is attached to the tubular member 57, and is adapted to be slidably engaged with the above-mentioned worm gear 22. The engaging member 54, slidably mounted, as at 55, to the base member 12, is provided with an extended element having a forked extremity 55', adapted to engage the tubular member 57, and the above-described construction is such as will permit the electric motor 39, or the coil spring 15 to operate our improved crib, as will be obvious by the above-described elements.

Referring in particular to Fig. 7 of the accompanying drawings, the circuit breaker 25 60, is attached to the extended element of the above-mentioned engaging member 54, and is adapted to break the electric circuit of the electric motor 39, when the above-mentioned crib is mechanically operated, so as to prevent the said electric motor 39 from being operated.

While we have above described the preferred form, construction and arrangement of the several elements employed, it will be understood that the device is, nevertheless, susceptible of considerable modification therein, and we therefore reserve the privilege of resorting to all such changes as may be fairly embodied within the spirit and scope of the invention as claimed.

Having thus described our invention, what we claim as new and desire to protect by Letters Patent of the United States is, as follows:

1. In a crib on wheels of the class described, the combination with a driveable disc supported on the bottom of the crib,

of an arm pivotally attached to the disc near its periphery, a lever pivotally attached at one end to the free end of the arm, a shaft 50 rotatably mounted to the crib, and having the other end of the lever attached thereto, a gear on the said shaft, a pinion meshing with the gear, and a shaft supporting the pinion, the latter mentioned shaft being connected with the wheels of the crib.

2. In a crib on wheels of the class described, the combination with a driveable disc supported on the bottom of the crib, of an arm pivotally attached to the disc near its periphery, a lever pivotally attached at one end to the free end of the arm, a shaft 60 rotatably mounted in bearings attached to the crib, and having the other end of the lever attached thereto, a gear on the said shaft, a pinion meshing with the gear, and a shaft supporting the pinion, the latter mentioned shaft being connected with the wheels of the crib.

3. In a crib on wheels of the class described, a disc rotatively mounted beneath the floor of said crib, driving mechanism operatively connected with said disc for continuously rotating the same in one direction, a rotatively mounted shaft on said crib for supporting the wheels thereof, a pinion on said shaft, a rod journaled on the floor of said crib, a gear meshed with said pinion and rigidly attached to said rod, and connecting mechanism comprising a crank rigidly attached to said rod and a link pivotally attached at one end to said crank and at the other end to said disc adapted to drive the wheels of said crib first in one direction and then in another and to produce a gradual decrease in the speed of rotation of said wheels before reversal of the rotation thereof and to produce a gradually increasing speed of rotation after the reversal of rotation thereof.

In testimony whereof we have affixed our signatures.

VIKTOR WEINBERGER.
MARTIN JAKOBOWITS,
